Term of patent 14 years

(Cl. D54—13)

FIG. 1

FIG. 2

FIG. 5

FIG. 3

FIG. 4

Fig. 1 is a perspective view of a burette holder, showing my new design;

Fig. 2 is a fragmentary top plan view;

Fig. 3 is a front elevational view;

Fig. 4 is a left end elevational view; and

Fig. 5 is a fragmentary bottom plan view.

The screw has been omitted from Figs. 2, 3 and 4 as a matter of convenience.

The dominant features of my design reside in the portions shown in full lines.

I claim:

The ornamental design for a burette holder, substantially as shown and described.
